UNITED STATES PATENT OFFICE.

AUGUST KAISER, OF NEW YORK, N. Y., ASSIGNOR TO THE EAGLE PENCIL COMPANY, OF SAME PLACE.

DESIGN FOR A LEAD-PENCIL.

SPECIFICATION forming part of Design No. 25,700, dated June 30, 1896.

Application filed April 30, 1896. Serial No. 589,799. Term of patent 7 years.

To all whom it may concern:

Be it known that I, AUGUST KAISER, a citizen of the United States, and a resident of the city, county, and State of New York, have invented a new and useful Design for Lead-Pencils, of which the following is a specification, reference being had to the accompanying drawings, forming part of this specification, in which—

10 Figure 1 is a perspective view of a pencil embodying my invention. Fig. 2 is a cross-section of the same intended to show more clearly the configuration of the pencil.

The external configuration of the pencil is

cylindrical, as shown at *a*, with three flat ¹⁵ wings or ribs *b* equidistant from each other, projecting laterally from the cylindrical body *a* and extending lengthwise of the pencil.

What I claim, and desire to secure by Letters Patent, is—

The design for a lead-pencil substantially as herein shown.

In testimony whereof I have hereunto set my hand this 24th day of April, 1896.

AUGUST KAISER.
